ASHTRAY

Albert Sebek, Cicero, Ill.

Application May 15, 1936, Serial No. 79,823

1 Claim. (Cl. 131—51)

This invention relates to ash trays having means for retaining lighted cigarettes or cigars so positioned and arranged respectively to the bowl of the tray that it is practically impossible for a lighted cigarette or cigar to drop from its retainer and burn the support on which the tray is mounted.

One of the objects of my invention resides in the novel design and construction of the retainer for the cigarettes or cigars which constitutes a unitary cast member of comparatively thin wall sections including a central supporting base portion having a pair of opposite and angularly disposed retaining arms formed integrally with said central supporting portion, each of said arms having an inwardly converging or wedge-like recess adapted to receive and frictionally retain a cigarette or cigar; the retaining portions of the arms being of comparatively thin and preferably 20 of rounded section to present a minimum of surface contact with a cigarette retained therebetween to thereby reduce to the minimum, or practically overcome, the objectionable condensation of moisture in the portion of the body of the cigarette engaged by the retainer.

Another feature of my invention is found in the angularly disposed retaining recesses which afford convenience and accessibility in inserting and removing the cigarette.

Another feature of my invention resides in the novel construction of the tray which includes the formation of the tray of a preferably circular bowl-like structure of novel wall formation having a novel central integrally-formed support 35 adapted to support the cigarette retainer and an ornament with a single securing member such as a screw; the central support constituting a hollow upwardly disposed integral portion of the bowl-like tray body adapted to receive the securing member and to conceal it within the hollowed chamber of the central support.

With the above and other objects in view, my invention consists in the novel combination, construction and arrangement of the parts and members shown in preferred embodiment in the attached drawing, described in the following specifications and particularly pointed out in the appended claim.

In the drawing:

Fig. 1 is a plan view of an ash tray embodying my invention;

Fig. 2 is a section taken on line 2—2 of Fig. 1;

Fig. 3 is a section through the central retainer support showing a modified construction.

In the illustrations, the tray 10 is shown in the

form of a cast bowl-like circular structure having a downwardly and inwardly curved outer peripheral wall portion 10^a gradually extended into the annular intermediate horizontal or flattened portion 10^b forming the tray bottom and which flattened portion 10^b is extended in an inwardly and upwardly disposed circular wall formation constituting a centrally disposed circular hollow support 10^c having a flattened top 10^d.

The hollow support 10^c is provided in its top 10^d with an opening 10^e and an inner circular shoulder 10^f.

The cigarette or cigar retainer 12 is preferably formed of a single die-casting and comprises a comparatively thin central flattened supporting base portion 12^a having a centrally located aperture or opening 12^b and a pair of oppositely disposed arms 12^c formed integrally with the central portion 12^a.

The retaining arms 12^c are disposed angularly 20 upwardly from the center of the tray and are formed of comparatively thin section and with an inwardly downwardly converging or wedge-like recess 12^d adapted to frictionally retain a cigarette or cigar between the spaced fork-like portions 12^e which are preferably of rounded cross-section to present a minimum of surface contact with the body of a cigarette inserted therebetween.

Since the cigarette-retaining arms 12^c are 30 mounted in the center of the tray and well within its outer wall margin it is evident that all of the ash from a burning cigarette left in such retaining arm must fall within the bowl and that any remaining portion of a lighted cigarette if displaced from its support in the retainer would fall within the tray.

The retainer 12 may be cast with an integral boss 12^f of round or square section as preferably shown in Fig. 2, and the opening 10^e in the top 40 10^d of the support 10^c may be formed of a suitable section to receive such boss.

The retainer 12 is secured to the top of the support 10^c by means of a single screw 11 having its head in engagement with a washer 14 bearing against the shoulder 10^f and its inner end in threaded engagement with a cooperating member 15 in the form of a handle or pedestal having an arcuate or dished depression 15^a in its top constituting a snuffer against which the lighted end 50 of a cigarette may be pressed and extinguished by such temporarily maintained pressure.

In the modified construction shown in Fig. 3 the retainer 12 is of uniform section in its central portion, that is, the boss 12^f and washer 14 shown 55

in Fig. 2 are omitted and the retainer 12 is simply secured to the support 10^c by the screw 11 which extends through the openings in the top 10^D and retainer 12 into threaded engagement with the nut 13.

I claim:

In a combined cigarette holder and tray including a tray comprising a unitary body having a centrally disposed integrally-formed upstanding circular wall with a flattened aperture top wall constituting a hollow support, a cigarette retainer mounted on said support and having a substantially flattened central base portion with an aperture in register with the aperture in said

support, said retainer base portion having a pair of angularly outwardly and upwardly disposed integral arms extending in opposite directions, each of said arms having a downwardly inwardly converging recess defined by cigarette-retaining portions of comparatively small circular cross-section, an ornament mounted on said apertured base portion of said retainer and having an inferiorly threaded base, and a screw mounted within said support of said tray and extending through both of said apertures into threaded engagement with the threaded base of said ornament. 5 10

ALBERT SEBEK.
